UNITED STATES PATENT OFFICE.

MERLE J. WIGHTMAN, OF SEATTLE, WASHINGTON, ASSIGNOR, BY MESNE ASSIGNMENTS, TO RAILWAY'S ACCESSORIES COMPANY, OF SEATTLE, WASHINGTON, A CORPORATION OF WASHINGTON.

RAIL-JOINT.

1,343,070.

Specification of Letters Patent.

Patented June 8, 1920.

Application filed September 12, 1917. Serial No. 190,870.

To all whom it may concern:

Be it known that I, MERLE J. WIGHTMAN, citizen of the United States, residing at Seattle, in the county of King and State of Washington, have invented a certain new and useful Improvement in Rail-Joints, of which the following is a specification.

My invention relates to improvements in rail joints and more particularly it relates to improvements in rail joints, one of which is described in United States Letters Patent No. 1,183,260, granted to me on date of May 16, 1916 and the object of my present invention (like that of the invention disclosed by said Patent No. 1,183,260) is to provide a rail joint so constructed that the abutting ends of contiguous rails shall be so united that there shall be no relative motion of said abutting ends, and that any wave action under the weight of a passing train shall be the same through the rail joint as it is throughout the lengths of said rails, and that the top surfaces of the heads of said rails shall be maintained in alinement as rigidly and firmly as they would be if they were welded together; but, a further object of my present invention is to provide a rail joint which shall embody parts so constructed and so associated with the tie upon which said rail joint is located that said parts and said tie shall conjointly act as an anchor or anti-creeper, to prevent the joined rails from creeping or moving in lengthwise directions in response to the travel of heavily loaded trains on said rails.

I accomplish these objects by devices illustrated in the accompanying drawings, wherein—

Figure 1 is a plan view of the abutting end portions of two rails joined by a rail joint embodying my invention;

Fig. 2 is a view of the same in side elevation;

Fig. 3 is a view of the same in vertical section on broken line 3, 3 of Fig. 1; and

Fig. 4 is a perspective view of an important detail of the same.

Referring to the drawings, throughout which like reference numerals indicate like parts, the abutting end portions of two rails 5 and 6 are united by fish plates 7 and 8 which, in the usual manner, are fastened thereto by bolts 9 and 10.

As indicated in Figs. 1 and 3, each of the

fish plates 7 and 8 is provided with an integral flange, as flanges 11 and 12 respectively, that projects outwardly from its bottom edge portion for a distance beyond the adjacent edges of the base portions of the rails 5 and 6, a portion of the under side surface of said flange being evenly seated on the top surfaces of said base portions of the rails 5 and 6, and the surface of the top edge portion of said fish plate being in engagement with the under side surfaces of the heads of said rails 5 and 6.

The outer edges of the flanges 11 and 12 throughout the distance between their respective opposite ends are curved to form an arc of a true circle, as shown more clearly in Fig. 1.

The abutting end portions of the rails 5 and 6 being securely united by the fish plates 7 and 8, the flanges 11 and 12 of said fish plates are disposed in an arch-like relation to a supporting tie plate, of the form shown by perspective view in Fig. 4, the curved outer edges of said flanges 11 and 12 being disposed to engage with and to be supported by the upwardly diverging surfaces 14 of the inner sides of oppositely disposed curved flanges 15 and 16, respectively, which are integral with and project upwardly from two spaced horizontal portions 17 of said supporting tie plate.

As thus disposed, the abutting end portions of the rails 5 and 6 serve as the key member of an arch whose other members include the fish plates 7 and 8, their integral flanges 11 and 12, and the flanges 15 and 16 of the supporting tie plate.

It is manifest that by reason of the bolts 9 and 10, and the curved edges of the flanges 11 and 12 disposed in engagement with the surfaces 14 of the curved flanges 15 and 16, the rails 5 and 6 cannot be moved in endwise directions with respect to the supporting tie plate.

The supporting tie plate is disposed with its two spaced horizontal portions 17 resting on the top surface of a railroad tie 18, which horizontal portions 17 are united by integral flanges 19 which extend downwardly preferably in diverging planes from the opposite edge portions thereof to engage with the upper corner edges of the opposite vertical sides of said tie 18, as more clearly shown in Fig. 2. The angular

or inclined arrangement of the flanges 19 insures a snug engagement thereof with the railroad tie and provides an arrangement whereby the device wedgingly engages the tie to insure against sidewise movement of the device. This arrangement also enables the device to be firmly positioned on ties of differing widths as will be apparent.

- Between the two spaced flanges 15, and 10 between the two spaced flanges 16 of the supporting tie plate, the horizontal portions 17 are each provided with a recess, as recesses 20, through which a rail spike, like the rail spikes 21 and 22, may be driven to 15 extend downwardly into the railroad tie 18 until its head forcibly engages with the upper side of the edge portion of the adjacent one of the flanges 11 and 12 as indicated more clearly in Fig. 3.
- 20 Thus, the spikes 21 and 22, by their engagement with the walls of the recesses 20, act conjointly with the flanges 19 of the tie plate to anchor said tie plate against sidewise movements on the railroad tie 18, 25 while the curved surfaces 14 of the several flanges 15 and 16 by their confined engagement with the curved edges of the flanges 11 and 12, respectively, serve to anchor the fish plates 7 and 8 and the joined rails 5 30 and 6 against movements in lengthwise directions of said rails 5 and 6.

Obviously, the dimensions, and to some extent, the forms and arrangement of parts of my rail joint, may be changed without departing from the spirit of my invention.

What I claim is:

1. A rail joint of the class described which embodies a tie plate that includes two spaced and horizontally disposed flat portions that are integrally united by flanges which project downwardly from the side edge portions thereof, each of said flat portions being provided with a recess disposed in its inner edge portion, and both 40 of said inner edge portions having integral, curved flanges that project divergently upward therefrom.

2. A rail joint of the class described which embodies a tie plate that includes two spaced and horizontally disposed flat portions that are integrally united by flanges which project downwardly from the side edge portions thereof, both of the inner edge portions of said flat portions having integral, curved flanges that project divergently upward therefrom.

3. A rail joint comprising, in combination with a supporting tie having opposite flat vertical sides, a tie plate including a flat portion constituting a horizontal tie bearing surface, and dependent flanges integral with said flat portion and inclined outwardly from the vertical to produce angular engagements thereof with the flat vertical sides of the tie, said flanges projecting

downwardly from the opposite side edges of said flat portion.

4. A rail joint comprising, in combination with a supporting tie having opposite flat vertical sides, a tie plate including a 70 pair of spaced horizontal flat portions united by dependent flanges which project downwardly from the opposite side edges of said flat portions, said flanges being inclined outwardly from the vertical to 75 produce angular engagements thereof with the flat vertical sides of the tie.

5. A rail joint including a tie plate having a pair of spaced oppositely longitudinally curved flanges that project upwardly 80 therefrom.

6. A rail joint including a tie plate having a pair of spaced oppositely longitudinally curved flanges that project divergently upward therefrom.

7. A rail joint including a tie plate having a pair of spaced side flanges connected by an outwardly curved upwardly extending flange.

8. A rail joint including a tie plate having a pair of spaced side flanges connected by an outwardly curved and outwardly inclined upwardly extending flange.

9. A rail joint including a tie plate having a pair of spaced side flanges connected by an outwardly inclined upwardly extending flange.

10. A rail joint including a tie plate having a flat horizontal portion provided with downwardly projecting spaced side flanges, 100 and spaced curved flanges projecting upwardly from said horizontal portion.

11. A rail joint including a tie plate having a flat horizontal portion provided with downwardly projecting side flanges, and 105 spaced curved flanges projecting divergently upward from said horizontal portion.

12. A rail joint including a tie plate having a flat horizontal portion provided with downwardly projecting side flanges, and 110 spaced flanges projecting divergently upward from said horizontal portion.

13. A rail joint including a tie plate having a flat horizontal portion provided with downwardly projecting and diverging side 115 flanges, and spaced curved flanges projecting upwardly from said horizontal portion.

14. A rail joint including a tie plate having a pair of spaced oppositely longitudinally curved flanges that project divergently upward therefrom, and a pair of fish plates having bottom flanges with outwardly longitudinally curved edges engaging the inner faces of said curved diverging flanges.

In witness whereof I hereunto subscribe my name this 10th day of September, A. D. 1917.

MERLE J. WIGHTMAN.
